ADVERTISING STRING HOLDER

William F. Vernon, Newton, Iowa

Application March 6, 1940, Serial No. 322,454

1 Claim. (Cl. 242—146)

This invention relates to a string dispenser of a type adapted for use as a fixture in retail grocery stores and markets and has for its primary object the provision of a dispenser capable of unusual economy of manufacture and designed to minimize the possibility of tangling of the string.

It is a further object of the invention to provide a string dispenser wherein a cone of string and string tensioning devices are concealed from view, and the dispenser is adapted to receive interchangeable advertising panels comprising substantially the entire exterior surface of the dispenser.

A further object of the invention is the provision of a string tensioning device of extreme simplicity capable of economical manufacture and quick and easy assembly and designed to prevent tangling of the string.

Referring now to the drawing:

Fig. 1 is a front elevational view of the essential elements of a string dispenser constructed in accordance with the principles of this invention;

Fig. 2 is a front elevational view similar to Fig. 1, showing the essential elements of the device in one of the positions assumed when string is being withdrawn from the mechanism; and

Fig. 3 is a plan view of the preferred embodiment of the invention showing a pair of assembled advertising panels positioned in the dispenser frame.

The frame 10 of the dispenser illustrated comprises a rectangular supporting structure which is preferably formed as a unit of one continuous length of heavy wire. The frame 10 includes a horizontal top portion 11 in which a center loop 12 is formed and a pair of vertical side portions 13 and 14 extending downwardly from the top portion 11 to support a horizontal lower portion 15. The lower portion 15 of the frame 10 includes an inverted V-shape spindle 16 extending upwardly at a point directly below the top loop 12 and formed of proper dimensions to engage the conical inner surface of a standard size cone or spindle 17 on which the string 18 is wound. The frame 10 comprises a complete rectangle and may be formed with the abutting ends of the wire in any convenient position, as, for example, at the point 21. In this connection it will be seen that the joint between the opposite ends of the wire frame 10 may be very conveniently reinforced by one of the vertical slides 22 or 23, which are preferably formed of thin sheet metal and spot welded to the vertical side frame mem-

bers 13 and 14. From an examination of Figs. 1 and 3, it will be seen that these vertical slides 22 and 23 not only reinforce the vertical frame portions 13 and 14, but in addition provide vertical channels in which interchangeable and removable advertising panels 24 and 25 may be inserted. These panels 24 and 25 may be of any desired material, but are preferably of thin sheet metal having lithographed advertising copy on their outer face and are of such dimensions as to seat their edges firmly against the vertical slides 22 and 23 and bow outwardly at their center portions to provide adequate clearance for the maximum diameter of the cone of string 18.

To successfully dispense the string 18 from the cone 17 without tangling, it is essential to provide an arrangement of guide loops and a tensioning mechanism designed to take up the unnecessary slack in the string and to lift the free end of the string upwardly toward the body of the dispenser after each operation, as, for example, after the package has been wrapped, tied and the string broken off.

In the present invention there are two of these guide loops 26 and 27, each of which is coiled from an identical length of wire, such as the wires 28 and 29, and these wires 28 and 29 are secured in vertical position between the top portion 11 and the bottom portion 15 of the frame in any convenient manner, as, for example, by spot welding at the points 31. Before being welded, however, a heavy metal tensioning ring 32 is positioned on the lower portion of the vertical wire 28 in such a manner that the wire will act as a vertical slide for the tensioning ring, which will then be free to move from the lower frame portion 15 upwardly along the wire 28 to the guide loop 26.

To prepare the dispenser for operation, the string 18 is threaded through the top loop 12, thence through the guide loop 27, across the frame and through the tensioning ring 32, and thence upwardly through the guide loop 26 and downwardly out of the dispenser.

In operation, when the clerk grasps the outwardly extending portion of the string 18 and draws the string from the mechanism, the string will slide through each of the several guide loops, but the friction of the string will exert a certain small amount of resistance sufficient to cause the tensioning ring 32 to be lifted upwardly along the vertical slide 28 to any point between the lower frame 15 and the guide loop 26. It will be understood that the ring 32 may rise completely to the guide loop 26 or only part of the distance

depending on the abruptness with which the string is drawn from the dispenser, but in any event, it will be seen that this ring will from time to time traverse the entire distance between the wire frame portion and the guide 26.

To avoid tangling, it is essential that the mechanism be designed so that parallel lengths of the string lying close together cannot intertwine with each other due to the inherent tendency of the string to coil and twist. In this connection it will be readily appreciated that when the string 18 is drawn quickly from the cone 17, the length of string extending from the cone upwardly to the center of the loop 12 may from time to time assume a multitude of different positions, but the arcuate shape illustrated at 18A in Fig. 2, is characteristic.

It will be noted that the string in this instance approaches the center guide loop 12 at a considerable angle with respect to a vertical line position passing through this loop and it is, therefore, desirable that the downwardly extending length of string 18b be arranged at an angle large enough to avoid the portion 18a at any point during the swinging movement around the axial center of the cone 17. This is accomplished in the present device by training the string portion 18b downwardly at an angle of approximately 45° and thence through the guide loop 27.

To prevent tangling of the string during its passage through the tensioning device, it is also desirable that the string be fed to the tensioning ring 32 at a large angle with respect to the vertical slide 28 and this is also accomplished in the present invention, as indicated by the position of the string portion 18c in Fig. 2.

To fully appreciate the importance of this construction, it should be kept in mind that the tensioning device must be of extreme simplicity in low-cost mechanisms of this kind and yet must be capable of unfailing operation at all times. The ring and slide wire arrangement is

to be preferred over any other type of tensioning mechanism from the standpoint of cost of manufacture, but with this type of tensioning means there has been in the past a tendency to tangle in the event that the string was jerked sharply in such a manner as to cause the ring 32 to bounce or gyrate and spin around the wire 28 in such a manner as to wind the string around the wire.

10 This objection has been overcome in the present invention by feeding the string to the tensioning ring 32 at a relatively large angle as indicated at 18c, for under these circumstances the tension of the string 18c will act on the ring 32 sufficiently to prevent any gyration or spinning irrespective of how sharply or abruptly the string may be jerked from the dispenser.

15 While I have shown and described the preferred embodiment of the invention in compliance with the patent statutes, it is subject to numerous modifications and alterations without departing from the inventive spirit and I therefore wish to be limited only by the scope of the appended claim.

20 I claim:

25 In an advertising spool-string dispenser; a wire frame having top, side, and bottom wires, including a string-spool spindle on the bottom wire; a top string guide and dispenser suspending loop on the top wire above the spindle; 30 guide wires having string guide loops mounted on the top and bottom wires closely paralleling the side wires; V-shaped retainer strips fastened on the side wires; a gravity operated string 35 tensioning member mounted for vertical movement on one of the guide wires; and removable side panels mounted within the retainer strips, the side panels being sufficiently stiff and long to require outwardly tensioned bowing to stably 40 enclose the string dispenser and provide effective removable advertising panels.

WILLIAM F. VERNON.
